ATTENTOR

Ernest Kaupmann

Dec. 1874

Ernest Kauffmann, of Philadelphia, Penn.
Letters Patent, No. 1876 Dated Dec. 16th 1868.

Design for a Metal Tea Set

The schedule referred to in these Letters Patent and making part of the same.

Scall whom it may concern:

Be it known that I, Ernest Kauffmann, of Philadelphia, in the County of Philadelphia, and State of Pennsylvania, have invented or produced a new and original Design for a Metal Tea Set, and I do hereby declare that the following is a full, clear, and exact description of the same, reference being had to the accompanying drawings, making

{ 13

Dec. 1876

portions of the several pieces are of ellipsoidal form. The spouts, are of curved form and have their lower ends, as well as the lower ends of the handles provided with ornaments k.

The urn Figure 7, is provided with a leaf scroll ornament, l, at the lower part of its body or main portion, at the spigot or faucet side.

Having thus described my invention, what I claim as new and desire to secure by Letters Patent is,

The configuration of the parts herein shown, and described to form a new and original design for a metal tea set.
